UNITED STATES PATENT OFFICE.

JAMES H. TEVIS, OF AUSTIN, TEXAS.

WINDMILL.

SPECIFICATION forming part of Letters Patent No. 224,247, dated February 3, 1880.

Application filed December 13, 1879.

To all whom it may concern:

Be it known that I, JAMES H. TEVIS, of Austin, in the county of Travis and State of Texas, have invented certain new and useful 5 Improvements in Windmills; and I do hereby declare the following to be a full, clear, and exact description of the invention, such as will enable others skilled in the art to which it app pertains to make and use the same, reference 10 being had to the accompanying drawings, and to letters of reference marked thereon, which form a part of this specification.

My invention relates to self-regulating windmills; and it consists in the construction and 15 arrangement of devices whereby the force of the wind is made to move the wind-wheel and crank-shaft backward and turn the vane, and also in the devices for turning the vane at will, as will be hereinafter more fully set forth.

20 In the annexed drawings, Figure 1 is a side elevation of a windmill embodying my invention. Figs. 2, 3, and 4 are detailed views of parts thereof.

A represents the tower of the windmill, provided at its upper end with a tubular bearing, B, on which the turn-table C is placed and caused to turn.

The turn-table C is provided with suitable boxes or bearings a a, in which is placed the 30 wind-wheel shaft D, carrying at its outer end the wind-wheel E, of any suitable construction. The shaft D is movable longitudinally in its boxes a a, and is formed with an elongated crank, on which is placed a box, b, for the attachment of the pitman to pass through the tubular bearing B and connect by a swivel with the pump-rod.

On the end of the turn-table opposite to where the wheel E is located is pivoted or 40 hinged a forked casting, F, to which the vane G is rigidly secured. This wheel is held in line with the wind-wheel shaft by means of a cord or chain, d, and weight H, the cord or chain being attached to the inner end of the 45 vane and passing over a pulley, i, which is mounted in a post, h, swiveled in the end of an arm, I, attached to the turn-table, as shown.

On the casting F is a pin, e, which projects through a slot in the long arm of an elbow- 50 lever, J, which is pivoted at its angle on the turn-table. The short arm of this elbow-lever

is also slotted, and passes over the upper end of a lever, K, pivoted at its lower end to the side of the turn-table.

The weight H, holding the vane G in line 55 with the shaft D, presses the lever K against the end of said shaft, holding the wind-wheel forward. When the wind increases and the wind-pressure on the face of the wheel is greater than the controlling-weight, it forces 60 the crank-shaft back against the perpendicular lever K, and turns the same on its pivot. This, through the medium of the elbow-lever J, causes the vane G to turn, and as this vane always lies with the wind the turn-table will 65 also turn, and as the wind increases it will continue to turn off until the edge of the wheel is to the wind. As the wind lulls the weight H will right the mill before the wind.

In case of a whirlwind, the mill will revolve 70 on the thimble or tubular bearing B without disturbing the pumping parts, because the main pump-rod is to be swiveled on the lower end of the pitman-rod, as above stated.

When the mill is to be stopped from pumping the weight H is transferred from the cord d to a cord or chain, d', which is attached to the end of an arm, L, attached to the turn-table at right angles to the wind-wheel shaft. The cord or chain d' passes from said arm 80 over a pulley, i', mounted in a post, h', which is swiveled in an arm, I', attached to the vane G on the opposite side from where the arm I is located. The weight will then turn the vane so as to throw the wheel entirely out of 85 the wind.

The cords or chains d d' should be long enough so that the weight can be transferred from the ground at the foot of the tower.

I do not claim, broadly, the idea of turning 90 the regulating-vane by a backward movement of the wind-wheel and shaft, as I am aware that such has been done before.

Having thus fully described my invention, what I claim as new, and desire to secure by 95 Letters Patent, is—

1. In a windmill where the vane is operated by the thrust of the wheel, the combination, with the wheel and its shaft, of the lever K, elbow-lever J, pivoted casting F, with pin e, 100 vane G, arm I, attached to the casting F and provided with the swiveled post h, carrying

the pulley *i*, and the cord or chain *d* with weight *H*, all constructed and arranged to operate substantially as and for the purposes herein set forth.

5 2. The combination of the vane *G*, cord or chain *d'*, arm *L*, pulley *i'*, swiveled post *h'*, arm *I'*, and weight *H*, substantially as and for the purposes herein set forth.

In testimony that I claim the foregoing I have hereunto set my hand this 28th day of 10 November, 1879.

JAMES H. TEVIS.
